CLAIM

The ornamental design for a electroluminescent lamp or
similar article, as shown and described.

DESCRIPTION

FIG. 1 is a perspective view of a electroluminescent
lamp or similar article showing my new design; and
FIG. 2 is a top plan view thereof; and
FIG. 3 is a cross-sectional view thereof taken along the
line 3—3 of FIG. 2; and

FIG. 4 is a side elevational view thereof; and
FIG. 5 is a bottom plan view thereof.

FIG-1

FIG-2

FIG-3

FIG-4

FIG-5
